BY David E. Lain,

ATTORNEY.

UNITED STATES PATENT OFFICE.

GEORGE E. McMMASTER, OF BELLINGHAM, WASHINGTON.

MOVING COLORED-SHADOW AND FLASH-LIGHT SIGN.

1,410,489.

Specification of Letters Patent. Patented Mar. 21, 1922.

Application filed October 27, 1921. Serial No. 510,918.

To all whom it may concern:

Be it known that I, GEORGE E. McMMASTER, a citizen of the United States, and a resident of Bellingham, in the county of Whatcom 5 and State of Washington, have invented a new and useful Moving Colored-Shadow and Flash-Light Sign, of which the following is a specification.

My invention relates to improvements in 10 moving, colored-shadow and flash-light signs suitable for street use, and one of the objects of my improvement is to use a transparent, vari-colored cap mounted for rotation over an incandescent electric light by 15 hot air currents induced thereby to throw vari-colored shadows on translucent sign surfaces combined with another incandescent electric lamp which is illuminated intermittently; another object of my improvement 20 is to place one of said hooded lamps above another with said flash lamp in between with discs also between said hooded lamps to protect each from uncolored light from the other; another object of my improvement 25 is to mount said lamps on a hinged door closing one side of the sign box; another object of my improvement is to use a sign box in which said lamps are mounted 30 having three translucent sides adapted for painting signs thereon and a transparent bottom; and another object of my improvement 35 is to fasten a screen of fine wire over each of the sign-box sides except the top and side closed by said door and use a pane of clear glass over said screen to close the bottom of said box and a pane of translucent glass inside of said screens to close each of said three box sides.

I attain these objects with the device illustrated in the accompanying sheet of drawings in which Figure 1 is a plan view of the top of my sign box or lantern. Fig. 2 is a side elevation of the same. Fig. 3 is a rear elevation of the same and Fig. 4 is a plan view of the bottom with a portion broken away.

Similar characters refer to similar parts throughout. Certain parts are broken away to show other parts hidden thereby.

More particularly: The sign box is in the form of a lantern, as illustrated, and has an angle bar frame 5 and a dome-shaped cover 6. Ears 7, 7 are fastened to the bottom frame for hitching guy wires. A door 8 with hinges 9, 9 closes the side of the lantern to be placed next to the building. Said door

is fastened closed by screws 10, 10 into a side frame.

A ring 11 is fastened to the top of the lantern, and this is connected by link 12 to 60 a suitable bracket, not shown for attachment to the front wall of a building in order that the lantern may be suspended over the street as usual. A netting of fine wire 13 is soldered over the front and two side openings 65 of the lantern and also over the bottom opening. Panes of glass 14, 14 are fitted in each of the front and side openings. By preference, these panes are painted or otherwise frosted on the inside surface to make them 70 translucent. They are placed against the wire screen on the inside and retained by bolts α^{14} through strips β^{14} . A pane 15, preferably of clear glass, is placed over the bottom wire net 13. A lamp bracket 16 is 75 fastened to the inside of door 8 and connected with its inner end is lamp socket 17 into which is screwed incandescent electric lamp 18. A wire pivot is hooked around the lower part of lamp 18 and around the nib on 80 top of said lamp with its upper end standing over the medial line of said lamp. On top of said wire 19 is mounted air motor wheel 21 to which is fastened skirt 20 around said lamp. Skirt 20 is preferably made of 85 isinglass, while the air wheel is preferably made of thin sheet aluminum. On skirting 20 are painted designs in bright translucent colors. A disk 22 is fastened on top of socket 17 by lamp 18. This disk is large enough to 90 intercept light passing through the bottom of skirt 20 to prevent it from impinging on the panes in the sides of the lantern. Below bracket 16 is lamp bracket 23, also fastened to the inside of door 8 and has socket 24 95 screwed in its inner end. And in socket 24 is screwed lamp 25. A wire 26 is bent to hook over the stem and nib of lamp 25 and its upper end projects upward in the medial line of lamp 25. On wire 26 is mounted air-motor-wheel 28, preferably of thin aluminum. An isinglass skirt 27 is fastened to wheel 28 around lamp 25. Designs are painted on this skirt in bright colors. A disk 29 is suspended from disk 22 by flexible 100 metal cords 30, 30. This disk is large enough to intercept light which passes through openings in wheel 28 and otherwise would impinge on the panes in the sides of the lantern. A cable 31 of six insulated 105 wires passes through an insulator in door 8. This cable is composed of two wires from

each of lamps 18, 25 and 34. A lamp bracket ^{a³¹} is fastened to the inside of door 8 between brackets 16 and 23. On the inside end of this bracket is fastened socket 32 into which is screwed flashing plug 33. Into the lamp socket of said flashing plug is screwed incandescent lamp 34. This lamp preferably occupies a central location in the lantern and during operations it flashes on and off

10 intermittently under control of plug 33.

In operation: Electric current entering through cable 31 causes lamps 18 and 25 to glow continuously and the heat therefrom causes skirts 20 and 27 to revolve. Light 15 from said lamps passes through said skirts and impinges on panes 14, and since this light must pass through the translucent painted designs on the skirts it appears from the exterior of the lantern as moving 20 shadows of colors corresponding to the colors of the designs on said skirts. Meanwhile lamp 34 is flashing intermittently which causes said colored shadows to fade and brighten with the coming and going of said 25 flashes, thus adding to the irregularity and pleasing features of the appearance. The clear pane 15 in the bottom of the lantern permits white steady light from lamp 25 to pass directly through to the sidewalk below.

30 When screws 10, 10 are removed, door 8 can be swung outward on its hinges on dotted arc 8', Fig. 1, which gives easy access to the operative devices which are within the lantern when the door is closed.

35 Wire screens 13 offer little obstruction to the passage of light and prevent pieces of glass from falling to the sidewalk when the glass panes become broken.

Having thus disclosed my invention, what 40 I claim is new and desire to secure by Letters Patent, is,—

1. In combination, a sign box having openings covered by wire screen and closable with frosted glass plates from within, an 45 incandescent electric lamp mounted within said box, an air-motor wheel revolvable by air currents generated by heat from said electric lamp mounted for revolution over said lamp, and a transparent skirt having 50 designs in translucent colors thereon fastened to said wheel around said lamp.

2. In combination, a sign box having openings closable by translucent sheets, an incandescent electric lamp mounted in said 55 box, an air-motor wheel revolvable by air currents generated by heat from said lamp mounted for revolution over said lamp, a transparent skirt fastened to said wheel around said lamp and having designs in 60 translucent colors thereon, a flashing plug mounted in said box, and an incandescent electric lamp mounted in said plug.

3. In combination, a sign box having 65 openings closable by translucent sheets, an incandescent electric lamp mounted in said

box, an air-motor wheel revolvable by air currents generated by heat from said lamp mounted for revolution over said lamp, a transparent skirt having designs in translucent colors thereon fastened to said wheel 70 around said lamp, another incandescent electric lamp mounted in said box and means adapted to cause said other lamp to glow intermittently.

4. In combination, a sign box having 75 openings closable by translucent sheets, two incandescent electric lamps mounted in said box, one above the other, an air-motor wheel revolvable by air currents generated by heat from each of said lamps mounted for revolution over each of said lamps, a transparent skirt having designs in translucent colors thereon fastened to each of said wheels around each of said lamps, and a disk between said lamps adapted to prevent light 80 which passes from beneath said upper skirt from impinging on said translucent sheets and also adapted to intercept light which passes through said lower air wheel from impinging on said translucent sheets. 90

5. In combination, a sign box having 95 openings closable by translucent sheets and also having an opening closable by a hinged door, an incandescent electric lamp mounted on said door, an air-motor wheel revolvable by air currents generated by heat from said lamp mounted for revolution over said lamp, and a transparent skirt having designs painted thereon fastened to said wheel 100 around said lamp.

6. In combination, a sign box having 105 openings closable by translucent sheets; a plurality of incandescent electric lamps mounted in said sign box; an air-motor wheel, revolvable by air currents generated by heat from said lamps, mounted for revolution over each of said lamps; a transparent skirt having designs in translucent colors thereon fastened to each of said air-motor wheels and pendant around said lamp 110 thereunder; and disks between said lamps and said translucent sheets adapted to intercept light from the uncovered parts of said lamps.

7. In combination, a lantern-form sign 115 box adapted for hanging in a street having an opaque cover, an opaque hinged door closing one open side, three other open sides closable by translucent sheets and a bottom opening closable by a transparent sheet, a 120 plurality of incandescent electric lamps in said lantern adapted for continuous illumination mounted on said door and adapted to swing outside of said box with said door when the same is opened, an air motor wheel for each of said continuous electric lamps revolvable by heat from each of said lamps mounted for revolution over each of said lamps; a transparent skirt having designs in translucent colors thereon fastened to 125

130

each of said wheels about each of said lamps, means adapted to intercept light passing through said air wheels and from beneath said skirts from impinging on said translucent sheets, another electric lamp in said lantern, and means to cause it to glow intermittently.

8. In combination, a sign box adapted for hanging in a street, having an opening closable by a hinged door and also having other openings closable by translucent sheets; an incandescent electric lamp mounted on said door adapted to be within said box when

said door is closed and to pass through the door opening and be outside of said box 15 when said door is open; an air-motor wheel mounted for revolution over said lamp and revolvable by air currents generated by heat from said lamp; and a transparent skirt, having designs thereon in translucent colors, 20 fastened to said air-motor wheel and pendant around said lamp, and adapted to pass through said door opening and be outside of said box when said door is open.

GEORGE E. McMASTER.
